UNITED STATES PATENT OFFICE.

FRANK TODD, OF OAK PARK, ILLINOIS.

RADIATOR FOR AUTOMOBILES.

1,102,366.

Specification of Letters Patent.

Patented July 7, 1914.

Application filed October 14, 1911. Serial No. 654.

To all whom it may concern:

Be it known that I, FRANK TODD, a citizen of the United States, residing at Oak Park, in the county of Cook and State of Illinois, 5 have invented certain new and useful Improvements in Radiators for Automobiles, of which the following is a specification.

The present invention relates to radiators which are particularly adapted for use on 10 automobiles and other vehicles which are propelled by power derived from internal combustion engines, and in which lightness, compactness and efficiency are desiderata.

In the present state of the art, improvements in radiators for this purpose all have 15 as their objects the providing of radiators having these characteristics, and, in like manner, the object of the present invention is to provide a radiator of the class named, 20 improved to the extent that these characteristics are attained more satisfactorily than by other radiators with which I am familiar.

In one type of radiator of the class named, 25 the water to be cooled passes through vertical tubes extending from the inlet header to the outlet header and the heat of the water as it passes through the tubes is drawn off or conducted away from the water tube by sheet metal plates or strips (known as radiating strips) which are in heat conducting 30 contact with the tubes and have large superficial areas exposed to the air passing through the radiator, whereby the heat absorbed by said radiating strips is radiated 35 into the air and dissipated. In this type, each of the radiating strips is bent to form a series or successions of substantially U-shaped channels which open in opposite directions and which contact with the sides 40 of adjacent tubes, but this arrangement is open to the objection that wherever the closed bottom sides of the channels contact with the tubes there is a double thickness of metal through which the heat must pass in 45 passing from the water in the tubes to the atmosphere. In another type, this double thickness of metal is avoided by forming each U-shaped channel separate from every other, but this is open to the objection that 50 the handling of a multitude of these channels in assembling the parts, adds materially to the cost of production, besides which it is almost impossible to so accurately arrange such a multitude of parts that they will present, in appearance, a symmetrical whole. 55

One object of the invention is to avoid the duplication of the thickness of metal at the sides of the tubes and at the same time form a continuous radiating strip having a connected series of radiating channels. 60

Another object of the invention is to make adjustable the portions of the strip which connect the channels, so that they may be adjusted relatively to each other, whereby when the parts are assembled the front of 65 the radiator will present the appearance of a multitude of cells or openings symmetrically arranged relatively.

Another object of the invention is to provide a radiator having ample radiating capacity and at the same time being of minimum weight and requiring but a minimum quantity of sheet metal. 70

Another object of the invention is to arrange in the air passage, between adjacent 75 water tubes, two so called radiating strips which bear against each other and against the water tube, and are so shaped that they will provide a series of rectangular channels, the corners of which engage each other and 80 and are so that the vertical and horizontal walls align with each other, respectively, and thereby brace each other both vertically and horizontally.

Other objects of the invention will appear 85 hereinafter.

In the accompanying drawings which are made a part of this specification, Figure 1 is a front elevation of the core of a radiator, together with the upper and lower headers, 90 constructed in accordance with the invention, both horizontal and vertical portions being broken away to indicate indefiniteness of size, and the thickness of the sheet metal of which the several parts are formed being 95 exaggerated for the sake of clearness. Fig. 2 is a horizontal section of a portion thereof, on the line 2, Fig. 3, looking downward. Fig. 3 is a front elevation on a larger scale of the lower right hand corner of the core 10 shown in Fig. 1, a fragment of the lower header being shown in section. Figs. 4 and 5 are vertical sections thereof, on the lines 4—4 and 5—5, respectively, Fig. 2, looking rearward. Fig. 6 is a side elevation or face 10 view of one of the radiating strips. Fig. 7 is a diagrammatic view of a fragment of a blank from which it is formed.

The upper and lower headers are shown at 1 and 2, respectively. These headers are, 11

in fact, chambers for receiving from the water jacket of the engine the water to be cooled and for receiving the water, after it is cooled by the radiator and returning it to the water jacket in customary manner. The upper and lower headers are in internal communication with each other by a number of vertical tubes, 3, which are secured to the headers water-tight and which are preferably constructed as shown in Fig. 2. That is to say, each tube is made of a single piece of sheet metal bent upon itself about its longitudinal center to form a plait, 4, the sides of which have close contact with each other, whence the sheet is offset, as shown at 5, so that its parallel sides, 6, are sufficiently far apart to provide the necessary space for the passage of water from the upper to the lower header, the adjacent edges of the strip being united by a seam, 7, of any desired construction.

The several water tubes are arranged in a row extending from side to side of the radiator and are of sufficient depth from front to back to make only a single row necessary. The tubes are spaced apart to leave between them air passages in each of which is placed two radiating strips, 8, ^{8a} both of which are of precisely the same construction but which are arranged back to back, as it were, or with their similar features presented in opposite directions.

The chief object of the peculiar formation of these radiating strips is to provide each with a series of substantially U-shaped channels, 9, ^{9a}, the walls of which form three sides of a rectangle. The parallel side walls of each channel are in heat conducting contact with one of the tubes so that the heat of the water passing through the tube is first taken up by the walls of the tube, then conducted through said walls into the walls of the channels, 9, ^{9a} and thence through said walls, which have large radiating surfaces or superficial areas exposed to the air in the air passages aforesaid where it is dissipated. In order to insure contact between the parallel walls of the channels, 9, ^{9a} and the side walls of the tubes, the side walls of the channels are provided with short flanges, 10, ^{10a} which bear against the sides of the water tubes. These flanges occur only in rear of the plaits, 4, of the tubes, the parallel side walls of the channels being continued uninterruptedly to contact with the plaits as shown more clearly in Fig. 2. The front edges of the plaits of the channels of the radiating strips are flush so that after the parts are assembled and dipped in a solder bath, the front of the radiator will present the appearance of a multitude of square or substantially square cells which aline both vertically and horizontally and are without seams. As before intimated, the two radiating strips in each air passage

are arranged back to back so that the open sides of their channels will be presented in opposite directions, *i. e.*, toward the adjacent water tubes, and they are also arranged to alternate or break joints, considered horizontally or in horizontal tiers, so that their corners come in contact with each other, as shown more clearly in Figs. 3 and 5. The sheet metal of which these radiating strips are formed is very thin, and in order that the parallel, horizontal walls of the channels shall aline, precisely, and that the vertical walls of the channels shall also aline, precisely, the corners of the channels are provided with shoulders or offsets, 11. In theory these offsets are precisely one-half the thickness of the metal of which the strips are made, so that the horizontal walls of adjacent strips will bear against each other so as to afford, in effect, horizontal braces between the water tubes, and, in like manner, the vertical walls of the channels will form, in effect, a vertical brace between the upper and lower headers. In addition to forming a practically continuous vertical brace extending from header to header, a decided advantage in arranging the radiating strips back to back and so that the channels of one strip alternate with the channels of the other strip is that a double thickness of metal through which the heat must be conducted before reaching and being dissipated in the air in the air passages is avoided. It is manifest that if the radiating strip or strips were so arranged that the bottoms of the channels would lie flat against the sides of the water tubes, a double thickness of metal would occur and in addition to this the horizontal sides of the channels would not be braced from top to bottom of the radiator. This formation of U-shaped channels obtains at both the front and back of the radiating strips excepting that at the back the tubes are not plaited, as they are in front, and the parallel horizontal walls of the channels are not provided with the projections 12, which are the result of continuing them to meet the plaits, 4. By omitting these shoulders, 12, at the back of the radiator, the radiating strips may be drawn out from the front of the radiator, without disturbing the water tubes. At an intermediate zone, extending longitudinally of the strip from end to end, the several U-shaped channels are connected by means which will enable a number of said channels to be manipulated together, as a single entity and this is preferably done by making the channels of a blank consisting of a flat strip of sheet metal so cut that it will enable the parallel side walls of the several channels to be formed by bending portions of the blank at right angles to the general plane thereof, leaving an intermediate portion, 13, ^{13a} connecting the U-shaped channels thus formed,

10 said intermediate portion being bent in such manner as to draw the channels proper toward each other and leave them separated by any desired distance, the intermediate 5 connecting portion being also so bent that it will contact with the side of the adjacent tube. More specifically stated, it will be seen on reference to Fig. 7 that the entire radiating strip may be formed from a single 15 blank of flexible sheet metal (preferably copper) which is cut upon the full lines adapted to be folded upon the dotted lines. For instance, the portions lying between the 20 cuts, 14^a, form one complete U-shaped channel, 9, (or 9^a) with its flanges, 10, (or 10^a) and its projections, 12, as shown in Fig. 6. By reason of the inherent flexibility of the 25 sheet metal of which the radiating strips are made, the connections, 13 and 13^a, may be bent or adjusted into any desired shape so as to bring the channels, 9, 9^a, at the desired distance apart.

As shown in the drawings, the connecting 30 portions, 13, are so bent or adjusted that the space between the adjacent channels is the same as the space between the parallel walls of each channel, so that, in the completed structure, the air passages between the water tubes are reduced to numerous vertically and 35 horizontally aligned squares. The connecting portions, 13, are, however, preferably bent or adjusted so that they contact at the points, 14, with the sides of the adjacent water tubes and thus serve to brace the 40 structure horizontally. Furthermore, they are bent into the form of plaits the sides of which do not quite contact with each other and these plaits permit more or less yielding so that the adjacent channels, 9, are self-adjusting in the sense that they will accommodate 45 themselves to each other in assembling the parts. The bottoms of the channels are provided with perforations, 15, and the connecting portions are provided with perforations, 16, which result in reducing the weight of the radiator, as a whole, and at the same time establishing free communication between the several air spaces or passages through which the air may circulate. These 50 perforations 15 and 16 also serve as guides for holding the stock while it is being subjected to the action of the forming dies, it being understood that the perforations 15 and 16 are formed in the stock while it is in

the flat and before it is subjected to the action of the forming dies.

What I claim as new is:

1. A radiator having a pair of headers, parallel water tubes connecting them and spaced apart to leave air passages between them, and a pair of radiating strips arranged in each of said air passages, each of said radiating strips having along its opposite edges laterally projecting portions bent to form a plurality of channels each open 65 along one side, the open sides of all adjacent channels being presented in the same direction, the radiating strips of each pair being arranged back to back and with their channels alternating, the engaging corners of the 70 channels being shouldered or off-set so as to bring the walls of the channels into alinement.

2. A radiator having a pair of headers, parallel water tubes connecting them and 75 spaced apart to leave air passages between them, and a pair of radiating strips arranged in each of said air passages, each of said radiating strips having along its opposite edges laterally projecting portions bent to form a 80 plurality of channels each open along one side, the open sides of all adjacent channels being presented in the same direction, the strips of each pair being arranged back to 85 back and with their channels alternating, the engaging corners of the channels being shouldered or off-set so as to bring the walls of the channels into alinement, and portions connecting the channels.

3. A radiator having a pair of headers, 90 parallel water tubes connecting them and spaced apart to leave air passages between them, a pair of radiating strips arranged in each of said air passages, each of said radiating strips having along its opposite edges 95 portions that are bent to form channels, each open along one side, the open sides of all adjacent channels being presented in the same direction, the radiating strips of each pair being arranged back to back and with their 100 side walls in contact with the water tubes, respectively, the edges of the side walls being flanged to provide ample bearing surface for contacting with the water tubes.

FRANK TODD.
